UNITED STATES PATENT OFFICE.

OLAF HALVORSEN AND ALBION H. JOHNSON, OF CHICAGO, ILLINOIS; SAID JOHNSON
ASSIGNOR TO SAID HALVORSEN.

LEATHER-STAMPING MACHINE.

Application filed February 25, 1922. Serial No. 539,227.

To all whom it may concern:

Be it known that we, OLAF HALVORSEN and ALBION H. JOHNSON, citizens of the United States, residing at Chicago, in the county of Cook and State of Illinois, have invented new and useful Improvements in Leather-Stamping Machines, of which the following is a specification.

This invention relates to a machine for embossing or printing on various types of goods, and more particularly to a machine specifically designed for printing or embossing leather goods, and an object of the invention is to provide a machine as specified which is particularly designed for stamping gold leaf lettering upon leather articles of all types, by the hot printing process, the improved machine being designed to permit such stamping accurately and with minimum effort upon the part of the operator.

Another object of this invention is to provide a machine as specified which embodies a foot operated lever having a reciprocating rod carried thereby upon which the type holder is pivotally connected for movement into a loading or type receiving position or into a printing position at the will of the operator, without disconnecting it from its carrying reciprocating rod, thereby eliminating the inconveniences contingent with use of analogous machines of approved types now in use, and providing a machine which will permit the placing of desired type there-in or its removal therefrom in a minimum length of time and with minimum effort.

Another object of this invention is to provide, a novel form of lever construction for moving the type carrier into type receiving or unloading position, or into stamping position, which cooperates with the support of the type carrier for locking the latter in adjusted positions and also to provide means for electrically heating the type carrier and the type carried thereby, as heated type is necessary to obtain the best results in gold lettering or stamping on leather or analogous material.

Other objects of the invention will appear in the following detailed description taken in connection with the accompanying drawings wherein:

Fig. 1 is a side elevation of the complete stamping machine.

Fig. 2 is an enlarged front elevation of the stamping machine.

Fig. 3 is an enlarged fragmentary side elevation of the machine showing the type carrier in stamping position in solid lines, and in type receiving or unloading position in dotted lines.

Fig. 4 is a section on the line 4—4 of Fig. 2.

Fig. 5 is a horizontal section on the line 5—5 of Fig. 2.

Fig. 6 is a vertical section on the line 6—6 of Fig. 2.

Fig. 7 is a fragmentary view, partly in section illustrating the heating element.

Fig. 8 is a detail section taken on the line 8—8 of Fig. 3.

Referring more particularly to the drawings, the improved stamping machine comprises an article carrying table 1 which is supported by suitable supporting legs 2. A supporting arm 3 rises from the table 1 and has a bearing 4 on its upper forward end which bearing is located over the center of the table 1 and slidably receives the reciprocating rod 5. An operating lever 6 has its upper end pivotally connected to the upper end of the rod 5 as shown at 7 in Fig. 1 of the drawings, and the operating lever is pivotally supported from the supporting arm by a suitable support 8. The lever 6 extends downwardly beneath the table and forwardly between the supporting legs 2 thereof and has a stirrup 9 mounted upon its lower end for receiving the foot of the operator to permit the rod 5 to be forced downwardly. A spring 10 is connected to the lever 6 and to the table 1 for returning the lever to its normal position and moving the rod 5 upwardly in its guiding bearing 4. The lower end of the reciprocating rod 5 is forked as clearly shown at 11 providing spaced arms 12 and 12' which are pivotally connected by means of a pin 13 to the up-standing bosses 14 and 14' on the type carrier 15. The type carrier 15 comprises a main body 16 which is provided with a ledge or type supporting plate 17 over which type engaging dogs 18 are mounted for movement towards or from each other. The type engaging dogs 18 are provided with threaded bores 19 through which the feed screw 20 extends. The feed screw 20 is threaded oppositely from its center towards its end, that

is one end is provided with right hand threads while the other end is provided with left hand threads to permit movement of the dogs towards or from each other, synchronously by rotation of the feed screw. The feed screw 20 projects beyond the ends of the body 16 and has thumb nuts 21 mounted thereon for manually rotating it. Suitable washers 22 are clamped between the wing nuts 21 and the ends of the body 16, for forming closures for the longitudinal opening in the body in which the feed screw is mounted. The arm 14' of the body 16 has an operating handle 23 pivotally connected thereto as shown at 24. The end 25 of which, is angled and extends through an opening 26 in the arm 14' and is adapted to project into anyone of a plurality of openings 27 formed in the arm 12' of the fork 11 for locking the type carrier 15 in either a vertical printing position as shown in solid lines in Fig. 3 of the drawings or in a horizontal type receiving or discharging position as shown in Fig. 3 of the drawings. The hand grip carrying end of the lever or handle 23 projects at an obtuse angle from the arm 14', as clearly shown in Figs. 5 and 8 of the drawings to facilitate operation of the lever and movement of the type carrying member 15.

In gold letter stamping on leather, analogous material, it is necessary that the type or cut be heated to provide the proper adhesion of the leaf gold to the material being stamped and to provide for this heating of the type, an electrical heating unit 30 of any approved construction is attached to the back of the type carrier 15. The heating element 30 is incased in a suitable casing 31 and has a plug or switch structure 32 connected thereto which is adapted for connection through the medium of a socket 33 with any suitable source of electric current supply. The heating element 30 will heat the type carrier 15 and any type carried thereby.

Summing up, the operation of the improved leather stamping machine is as follows: the type carrier 15 is moved into its horizontal position as indicated in Fig. 3 of the drawings, and the desired type is placed upon the supporting plate 17 after which the gripping dogs 18 are adjusted to properly grip the type and hold it in place. The hand lever 23 is then moved upon its pivot 24 to release the type carrier 15 and the type carrier is swung, through the medium of the handle 23 into its vertical printing position as shown in solid lines in Fig. 3 of the drawings in which position, it is locked by means of the angled end 25 engaging in the uppermost opening 27 as shown in Fig. 6 of the drawings. The electrical current to the heating element 30 is then turned on and when the type carrier 15 and the type carrier thereby is heated to the proper degree,

the foot lever 6 is operated to force the type carrier 15 downwardly for impressing the letters or the like, carried by the type upon the material to be stamped. The usual process of gold letter stamping is employed in connection with the above operation.

It is, of course, to be understood that the invention may be constructed in other manners and the parts associated in other relations and, therefore, we do not desire to be limited in any manner except as set forth in the claims hereunto appended.

Having thus described our invention what we claim is:

1. In a stamping machine, a vertically movable supporting rod, a type carrier pivotally carried by said rod for movement into horizontal type receiving or unloading position and movement into vertical stamping position, a handle pivotally supported by said type carrier, and means formed upon said handle for cooperation with said rod to lock the type carrier in adjusted positions.

2. In a stamping machine, a vertically movable supporting rod, a type carrier pivotally carried by said rod for movement into horizontal type receiving or unloading position and movement into vertical stamping position, a handle pivotally supported by said type carrier, means formed upon said handle for cooperation with said rod to lock the type carrier in adjusted positions, and an electric heating element carried by said type carrier.

3. In a stamping machine, a vertically movable carrying rod, a foot lever connected to said rod for reciprocating it, the lower end of said rod being forked, a type carrier pivotally connected to said forked end, adjustable clamps carried by said type carrier, an operating handle pivotally connected to said type carrier, one arm of said fork provided with a plurality of openings, one end of said handle being angled for seating in one of said openings to lock said type carrier in adjusted positions.

4. In a stamping machine, a vertically movable carrying rod, a foot lever connected to said rod for reciprocating it, the lower end of said rod being forked, a type carrier pivotally connected to said forked end, adjustable clamps carried by said type carrier, an operating handle pivotally connected to said type carrier, one arm of said fork provided with a plurality of openings, one end of said handle being angled for seating in one of said openings to lock said type carrier in adjusted positions, and an electric heating element carried by said type carrier.

5. In a stamping machine, a vertically movable carrying rod, a foot lever connected to said rod for reciprocating it, the lower end of said rod being forked, a type carrier

pivottally connected to said forked end, said type carrier comprising a type supporting back plate, type clamps adjustably movable along said back plate for cooperation there-
5 with in supporting type, an electrically heating element attached to said back plate, an operating handle pivotally connected to said type carrier, one arm of said fork provided with a plurality of openings, one end of said
10 handle being angled for seating in one of said openings to lock said type carrier in adjust-
ed positions.

6. In a stamping machine, a vertically movable supporting rod, a type carrier adjustably carried by said rod, a handle pivotally supported by said type carrier, and
15

means formed upon said handle for coop-
eration with said rod to lock the type car-
rier in adjusted positions.

7. In a stamping machine, a vertically 20
movable supporting rod, a type carrier ad-
justably carried by said rod, a handle pivot-
ally supported by said type carrier, and
means formed upon said handle for coop-
eration with said rod to lock the type car-
rier in adjusted positions, and an electric
heating element carried by said type car-
rier.

In testimony whereof we affix our signa-
tures.

OLAF HALVORSEN.
ALBION H. JOHNSON.
